US00D842479S

(12) **United States Design Patent** (10) **Patent No.:** **US D842,479 S**
Rezach et al. (45) **Date of Patent:** **** Mar. 5, 2019**

(54) **SPINAL IMPLANT**

(71) Applicant: **Warsaw Orthopedic, Inc.**, Warsaw, IN (US)

(72) Inventors: **William Alan Rezach**, Covington, TN (US); **Dustin Bobbitt**, Olive Branch, MS (US)

(73) Assignee: **Warsaw Orthopedic, Inc.**, Warsaw, IN (US)

(**) Term: **15 Years**

(21) Appl. No.: **29/642,446**

(22) Filed: **Mar. 29, 2018**

Primary Examiner — Charles D Hanson

(57) **CLAIM**

The ornamental design for a spinal implant, as shown and described.

DESCRIPTION

FIG. 1 is a perspective view of a spinal implant; FIG. 2 is a front view of the spinal implant; FIG. 3 is a back view of the spinal implant; FIG. 4 is a side view of the spinal implant; FIG. 5 is a side view of the spinal implant; FIG. 6 is a top view of the spinal implant; and, FIG. 7 is a bottom view of the spinal implant.

The broken lines are for the purpose of illustrating structure and form no part of the claimed design.

1 Claim, 6 Drawing Sheets
